UNITED STATES PATENT OFFICE.

JOSEPH W. KNOTT, OF BEAVER FALLS, PENNSYLVANIA.

DESIGN FOR A HOPPER FOR COFFEE-MILLS.

SPECIFICATION forming part of Design No. 16,332, dated October 13, 1885.

Application filed July 9, 1885. Serial No. 171,128. Term of patent 7 years.

To all whom it may concern:

Be it known that I, JOSEPH W. KNOTT, a citizen of the United States, residing at Beaver Falls, in the county of Beaver and State of Pennsylvania, have invented and produced a certain new and original Design for a Hopper for Coffee-Mills, of which the following is a specification.

In the drawings, Figure 1 is a side elevation of my newly-designed hopper for coffee-mills arranged upon the ordinary case. Fig. 2 is a plan view of the same.

To secure an ornamental appearance, I so form my hopper as to present a substantial rectangular cross-section or plan, there being four sides, *a*, each contracting toward the base or flange *b*, so that the hopper approximates in outline an inverted truncated pyramid, the corners of which are square, as shown, or 20 slightly rounded.

The base, which may form part of or be sep-

arated from the hopper, is quadrangular in shape, and is provided with an outer rim or flange, *b*.

The leading feature of my design is the hopper quadrangular in cross-section, and provided with a flange at the bottom following the configuration of the wall of the hopper.

I claim—

The design for a hopper for coffee-mills, consisting of a hopper quadrangular in cross-section, and provided with a flange at the bottom following the configuration of the wall of the hopper, substantially as described.

In testimony whereof I have signed my name to this specification in the presence of two subscribing witnesses.

JOSEPH W. KNOTT.
